UNITED STATES PATENT OFFICE

2,494,190

MULTIPLE GAS BURNER WITH PRESSURE-GOVERNED VALVES

Henry S. Minster, Rosemont, Pa., assignor to
 Roberts & Mander Corporation, a corporation
 of Delaware

Application December 4, 1945, Serial No. 632,623

6 Claims. (Cl. 158—105)

1

This invention relates to a burner unit and more particularly to that type of burner unit referred to as double-duty, having high and low flame chambers usually designated as simmer and main gas chambers.

While such burners are in common use, those of which I am familiar with are usually provided with a pair of mixer tubes communicating with the several chambers and with a dual valve which directs gas to one or the other of these tubes. Such a structure is obviously costly to manufacture and an important object of the invention is the provision of a burner of this character requiring only a simple control valve and a single mixer tube.

A further and more specific object of the invention is the provision in a structure of this character, of an arrangement whereby selection of the chamber operating may be made by simple adjustment of an ordinary valve, the selection of the chamber occurring as a function of the pressure formed in the mixer tube. These and other objects I attain by the construction shown in the accompanying drawings wherein:

Fig. 1 is a plan view partially broken away of a gas burner embodying my invention; and

Fig. 2 is a transverse sectional view therethrough.

Referring now more particularly to the drawings, numeral 10 designates a burner body having, as at present illustrated, an inner or main burner chamber 11 and an outer or simmer chamber 12 provided with the usual gas outlet ports 13. A single mixer tube 14 is provided having an ordinary control valve 15 by means of which gas is supplied to the tube. This tube underlies both chambers 11 and 12 at its burner engaging end and is separated therefrom by a partition plate 16. Partition plate 16 has ports 17 and 18 communicating with chambers 11 and 12, respectively. These ports being controlled by valves 19 and 20 which, as at present illustrated, are pivotally connected to a lever 21 pivoted to the under surface of the partition plate as at 22.

As will be noted, the port 17 which communicates with the main burner chamber is a considerably greater area than the port 18 and the valve controlling the port 17 is correspondingly larger than the valve 20 controlling port 18. This, plus an unbalanced condition in lever 21 results in maintenance of valve 20 in a normally open position and valve 19 in a normally closed position. This condition will be maintained as long as the opening of valve 15 does not create sufficient back pressure in tube 14 to disturb the balance. When,

2

however, the valve 15 is sufficiently opened, the pressure in tube 14, acting upon valve 19, will open the same, admitting gas to the main burner chamber and moving the simmer chamber valve 20 toward closing position. Obviously, the pressure need not entirely close valve 20 in which event the burner ports 13 of both chambers are effective.

The illustrated method of obtaining the balance between valves 19 and 20 necessary to prepare control of the burner chambers is obviously but one of many possible arrangements and I accordingly do not wish to be understood as limiting myself to this structure except as herein-after claimed.

I claim:

1. In a double-duty gas burner, a pair of burner chambers, a single tube to supply both said chambers with a combustible mixture, one of said chambers being normally in communication with said tube and means controlled by pressure in said tube for establishing communication between said tube and the second chamber and terminating communication between the first chamber and the tube.

2. In a double-duty burner a pair of burner chambers, a single tube to supply both said chambers with a combustible mixture, valved ports connecting said tube and said chambers, the valve of one of said ports being normally closed and of the other thereof normally open and means controlled by the pressure in said tube for reversing the positions of said valve.

3. In a double-duty burner a pair of burner chambers, a single tube to supply both said chambers with a combustible mixture, valved ports connecting said tube and said chambers, a connection between the valves, including a biasing means normally maintaining one of the valves open and the other thereof closed, said biasing means yielding at a predetermined pressure in said tube to permit such pressure to open the last named valve.

4. In a double-duty burner a pair of burner chambers, a single tube to supply both said chambers with a combustible mixture, valved ports connecting said tube and said chambers, a connection between the valves, including a biasing means normally maintaining one of the valves open and the other thereof closed, said biasing means yielding at a predetermined pressure in said tube to permit such pressure to open the last named valve, and close the first named valve.

5. In a double-duty burner a pair of burner chambers, a single tube to supply both said cham-

bers with a combustible mixture, valved ports connecting said tube and said chambers, the valves of said ports seating toward the tube and having different areas exposed to pressure in said tube, and a pivoted lever connecting the valves of said ports and eccentrically pivoted intermediate its ends to provide with said valves a structure unbalanced in favor of the larger valve so that the latter normally is closed and the other valve open but is yieldable at a predetermined pressure in the tube to cause such pressure to open said heavier valve and close said other valve.

6. In a double-duty burner a pair of burner chambers, a single tube to supply both said chambers with a combustible mixture, valved ports connecting said tube and said chambers, the valves of said ports seating toward the tube and having different areas exposed to pressure in said tube, and a connection between said valves pivot-

ally supported and providing with said valves a structure unbalanced in favor of the valve of greater area so that the latter normally is closed and the other valve open but is yieldable at a predetermined pressure in the tube to cause such pressure to open said valve of greater area and close said other valve.
